Primary Examiner — Kelley A Donnelly(74) Attorney, Agent, or Firm — Law Office of Michael O'Brien(57) CLAIM

An ornamental design for a combination mat and serving tray, as shown and described.

DESCRIPTION

FIG. 1 is a front perspective view of a new design for a combination mat and serving tray;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The solid line showing illustrates the claimed features within the design for the claimed article of manufacture. The shading is provided to illustrate contour only and is not an indication of texture, gloss, etc.
